SPRAYING MACHINE

Harry C. Cole, Philadelphia, Pa.

Application January 16, 1930, Serial No. 421,112

8 Claims. (Cl. 299—86)

The principal object of the present invention is to spray liquid upon surfaces, such as paper and the like, in substantially the same form and character of appropriate spray but in the same 5 or different quantities per unit of time. Another object of the invention is to provide for spraying liquid in an appropriate character of spray and in what may be regarded as relatively large quantities in comparison with spraying machines now 10 in use, for example, principally for spraying melted paraffine in the printing industry in which the quantity of paraffine sprayed per unit of time is very small. Another object of the invention is to make the character of the spray substantially 15 independent of the quantity of liquid or fluid sprayed per unit of time.

Other objects of the invention will appear from the following description and the invention, generally stated, may be said to comprise a machine 20 for spraying liquid in substantially the same form and character of spray and in the same or different quantities per unit of time which includes a reservoir exposed to atmospheric pressure provided with a nozzle and with pneumatic means 25 adapted for cooperation with the nozzle to provide a spray of desired form, a pressure chamber having an orifice arranged to discharge liquid into the reservoir in quantity proportionate to the pressure in the chamber, and means for varying 30 the pressure of the liquid in the chamber to pass different quantities of liquid through the orifice per unit of time, whereby changes in the form of a jet escaping through the orifice induced by different pressures are not reflected in the form 35 or character of the spray provided at the nozzles.

The invention also comprises the improvements to be presently described and finally claimed.

In the following description reference will be 40 made to the accompanying drawing forming part hereof and in which

Figure 1 is a diagrammatic view partly in vertical section and partly in elevation.

Fig. 2 is a horizontal section taken on the line 45 2—2 of Figure 1, and

Fig. 3 is a detached view of one of the parts hereinafter described.

Referring to the drawing 1 is a reservoir and it is shown as provided with a tangentially ar- 50 ranged inlet 2 vented to the atmosphere as by means of the duct 3, so that the reservoir is ex- posed to atmospheric pressure which is substan- tially constant. The reservoir 1 is provided with a nozzle 4 shown as communicating with the base of the reservoir. Within comparatively wide

limits the size of this nozzle is not important al- though it should be in general appropriate to the upper and lower limits of the quantity of liquid that is likely to be required per unit of time. There are pneumatic means adapted to cooperate 5 with the nozzle 4 to provide a spray of the desired form and character and the form and character of the spray is under control and may be appropriately varied or adjusted. As shown these means comprise a protection plate 5, an inter- 10 mediate plate 6 somewhat shorter than the plate 5, and an air liner 7. These parts extend across the device shown in Fig. 2 which includes a rep- etition of the elements already described. How- 15 ever, the air liner 7 is notched as at 8, Fig. 3, and the notches communicate with passages 9 leading from an air trunk 10 that extends across the machine or device and to one end of which air under pressure is supplied by means of the connection 11. The pressure of the air supplied 20 to the connection 11 is under control. 12 is a pressure chamber shown to extend across the de- 25 vice and having an orifice 13 arranged to dis- charge liquid into the reservoir 1, or more ac- curately, into the tangentially arranged inlet pas- sage thereof. 14 represents means for intro- 30 ducing liquid under pressure into the chamber 12. The liquid supplied through the connection 14 may be of substantially any character and water is an example. The connection 14 is 35 shown as provided with a pressure gauge 15 and with a pressure reducing valve 16. 17 is a screen for excluding foreign matter from the orifice 13. There are means for cleaning the orifice 13 and they are shown to comprise a pin 18. There are 40 a number of these pins 18 and each is guided at one end by a tubular guide 19. At the other end the pins are connected to a bar 20 slid able in ways 21. There are links 22 pivoted at one end to brackets 23 and they engage the bar 20, and the other ends of these links are connected with a rod 24. The rod 24 is connected to the piston 25 of the cylinder 26. The cylinder 26 is con- 45 nected with a pressure pipe 27. By cutting off pressure and exhausting either the cylinder 26 or the chamber 12, by means of the valves 28 or 29, it is possible to project the pins 18 into the orifices 13 and to retract the pins from those orifices thus cleaning the latter.

The mode of operation of the device may be 50 described as follows:

Under any given condition of pressure of liquid in the chamber 12 the quantity of liquid passing through the orifice 13 into the reservoir 1 per unit of time is a function of the pressure 55

and is constant. If the pressure is increased the rate of flow through the orifice 13 is increased, and if the pressure is decreased the rate of flow through the orifice 13 is decreased. However, 5 such variations of flow through the orifice would effect the form and character of the jet or supply passing therethrough, and if that jet were used for spraying, the form of spray would change and likely become inappropriate for the 10 intended purpose. However, whatever changes may occur or conditions prevail at the orifice 13, the form of flow from the nozzle 4 is not affected thereby since the pressure in the reservoir 1 is substantially constant, so that although the 15 quantity of liquid leaving the nozzle 4 per unit of time can be increased or diminished by changing the pressure in the chamber 12, still the character of the spray is controlled by the air escaping through the notches 8, and it can be made of any form and character desired. From 20 the foregoing description it will be understood that the spray provided across the device is uniform although it can be varied as to quantity while preserving an appropriate form or character. 25

It will be obvious to those skilled in the art to which the invention relates that modifications may be made in details of construction and arrangement and matters of mere form without departing from the spirit of the invention which is not limited to such matters or otherwise than the prior art and the appended claims may require.

I claim:

- 35 1. A machine for spraying liquid in substantially the same form and character and in constant quantity per unit of time comprising in combination a reservoir exposed to atmospheric pressure and provided with a permanently open nozzle and with pneumatic means adapted for cooperation with the nozzle to provide a spray and control the form and character thereof, a closed pressure chamber having an orifice permanently open in operation and arranged to discharge liquid into the reservoir in quantity proportionate to the pressure in the chamber, and means for supplying liquid under pressure to the chamber to fill the chamber with liquid under pressure.
- 40 2. A machine for spraying liquid in substantially the same form and character and in constant quantity per unit of time comprising in combination a reservoir exposed to atmospheric pressure and provided with a permanently open nozzle and with pneumatic means adapted for cooperation with the nozzle to provide a spray, a closed pressure chamber having an orifice permanently open in operation and arranged to discharge liquid into the reservoir in quantity proportionate to the pressure in the chamber to 45 fill the same with liquid under pressure, means for supplying liquid under pressure to the chamber.
- 45 3. In a machine for spraying liquid the combination of a reservoir vented to the atmosphere, a permanently open nozzle arranged to discharge from the reservoir, pneumatic means for cooperation with the nozzle to provide a spray, an orifice permanently open in operation and at the inlet of the reservoir, and closed means for discharging fluid under different pressure 50 through the orifice into the reservoir.
- 50 4. In a machine for spraying liquid the combination of closed means including an orifice permanently open in operation, means for passing fluid under pressure into the first mentioned means to fill the same and through the orifice, a reservoir having means for maintaining substantially constant pressure within it and into which the orifice discharges, a permanently open nozzle through which the reservoir discharges, 55 and pneumatic means cooperating with the nozzle.
- 55 5. In a machine for spraying liquid the combination of a series of reservoirs each having a permanently open discharge nozzle and pneumatic spray means and each vented to the atmosphere, a closed pressure chamber common to the reservoirs and having orifices permanently open in operation and respectively communicating with the reservoirs, and means for introducing a supply of liquid under pressure in the pressure chamber to keep the same full of liquid under pressure.
- 60 6. A spraying device of the character described including reservoirs vented to the atmosphere, a nozzle and its complemental pneumatic device for each reservoir, a pressure chamber having a series of orifices communicating respectively with the reservoirs, pins arranged in the chamber and projectable and retractable in respect to the orifices, and piston and cylinder devices and their connections for actuating the pins.
- 65 7. In a machine of the class described permanently open spraying devices, means for feeding liquid to the spraying devices which comprise permanently open orifices, vented reservoirs into which the orifices discharge and which are arranged to supply the spraying devices, closed pressure chambers for discharging liquid under pressure through the orifices and means for feeding liquid under pressure to the pressure chambers.
- 70 8. In a machine of the type described spraying devices including vented reservoirs, permanently open orifices adapted to discharge into the reservoirs, and means for discharging liquid under controlled pressure through the orifices which include closed pressure chambers, and means for supplying liquid under pressure to the chamber.

ber, and means for varying the pressure of the liquid supplied to the chamber.

3. In a machine for spraying liquid the combination of a reservoir vented to the atmosphere, a permanently open nozzle arranged to discharge from the reservoir, pneumatic means for cooperation with the nozzle to provide a spray, an orifice permanently open in operation and at the inlet of the reservoir, and closed means for discharging fluid under different pressure 10 through the orifice into the reservoir.

4. In a machine for spraying liquid the combination of closed means including an orifice permanently open in operation, means for passing fluid under pressure into the first mentioned means to fill the same and through the orifice, a reservoir having means for maintaining substantially constant pressure within it and into which the orifice discharges, a permanently open nozzle through which the reservoir discharges, 20 and pneumatic means cooperating with the nozzle.

5. In a machine for spraying liquid the combination of a series of reservoirs each having a permanently open discharge nozzle and pneumatic spray means and each vented to the atmosphere, a closed pressure chamber common to the reservoirs and having orifices permanently open in operation and respectively communicating with the reservoirs, and means for introducing a supply of liquid under pressure in the pressure chamber to keep the same full of liquid under pressure.

6. A spraying device of the character described including reservoirs vented to the atmosphere, a nozzle and its complemental pneumatic device for each reservoir, a pressure chamber having a series of orifices communicating respectively with the reservoirs, pins arranged in the chamber and projectable and retractable in respect to the orifices, and piston and cylinder devices and their connections for actuating the pins.

7. In a machine of the class described permanently open spraying devices, means for feeding liquid to the spraying devices which comprise permanently open orifices, vented reservoirs into which the orifices discharge and which are arranged to supply the spraying devices, closed pressure chambers for discharging liquid under pressure through the orifices and means for feeding liquid under pressure to the pressure chambers.

8. In a machine of the type described spraying devices including vented reservoirs, permanently open orifices adapted to discharge into the reservoirs, and means for discharging liquid under controlled pressure through the orifices which include closed pressure chambers, and means for supplying liquid under pressure to the chamber.

HARRY C. COLE.
